UNITED STATES PATENT OFFICE.

ARTHUR C. ARMSTRONG, OF HAMMOND, INDIANA.

PROCESS OF AND APPARATUS FOR THE DISTILLATION OF OIL.

1,408,242.

Specification of Letters Patent. Patented Feb. 28, 1922.

Application filed January 5, 1918. Serial No. 210,582.

To all whom it may concern:

Be it known that I, ARTHUR C. ARMSTRONG, a citizen of the United States, residing at Hammond, in the county of Lake 5 and State of Indiana, have invented new and useful Improvements in a Process of and Apparatus for the Distillation of Oil, of which the following is a specification.

My invention relates to improvements in 10 apparatus for the distillation of hydrocarbons and the like, and the process of their distillation. It has for one object the separation in one process by sectional condensation and separation, of petroleum distillate 15 of various vaporization points, and is particularly adapted for the refinement of gasoline. It has for further object to provide an apparatus and a process for refining gasoline which permits the operation of the still 20 at a relatively low temperature, and thus allows its operation for a longer period without the risk of overheating the bottom of the still met with in the present apparatuses and processes. Another object is the provision 25 of an apparatus for the distillation of hydrocarbons and the like in which the vapor can be passed through the condensing section at a lower pressure than is usually used. A further object is the provision of 30 a still in which no low grade condensate can gather in the condensers and lie there, or be carried upward or forward by the pressure of the vapor or otherwise, so as to be mixed with the higher grade condensate. 35 Another object is the provision of an apparatus and a process in which the necessary pressure is reduced by the fact that the vapor and the condensate always flow in the same direction, through the pipes and condensation passages. Other objects will appear in the specification from time to time.

My invention is illustrated in the accompanying drawings, wherein—

Fig. 1 is a side view with parts in section 45 of the whole apparatus;

Fig. 2 is a section along the line 2—2 of Fig. 1.

Like parts are indicated by like letters throughout the several figures.

50 A is the usual type of still with a feed pipe A¹, and heating means A² of any preferred practical form. From the upper surface of the still extends the vapor pipe B closed shortly above the still by the valve B¹. 55 The vapor pipe rises substantially vertically

to the bend B², by which it is recurved to deliver its contents vertically downwardly into the lateral distribution pipe C. Lying directly below the lateral distribution pipe is a condensation chamber D, of approximately 60 the same length as the distribution pipe, but of much greater breadth, height, and volume. Connecting the distribution pipe and the condensation chamber, are a plurality of series of parallel vertical radiation pipes E, 65 preferably but not necessarily arranged in three parallel, vertical planes. The number of pipes may be varied, of course, to suit the individual requirements. This arrangement of distribution pipe, radiation 70 pipe, and condensation chamber, is normally the same in all the various radiation sections illustrated in Fig. 1, though it will be understood that the size of the parts, and the number and length of 75 the pipes can be varied if found necessary. From the bottom of the condensation chamber flows an oil return pipe F, which leads into the pipe G, down which drains back to the still the lower grade condensate from 80 a plurality of the lower condensation sections. The condensate of the first condensation section flows through the pipe F and the pipe G, reaching the still at a point below the oil level. The pipe G is closed by a valve G¹ which is normally 85 opened at a point adjacent the still. From the upper surface of the condensation chamber D, leads a vapor pipe H, which carries the uncondensed vapor upward around a band H¹ and downward into a radiation and condensation section normally 90 identical with the one above described. At the bottom of the condensation chamber is a pipe I, through which passes the heavy condensate into the pipe already described, 95 reaching the still in the same manner and at the same place as the condensate from the first section. A vapor pipe J carries the vapor again upwards and in the same manner to the top of a third similar condensation section, whence the heavy condensates escape through the pipe K, and then through 100 the pipe G to the still. The vapor pipe L carries the uncondensed vapor upward to the top of a fourth condensation section. To 105 the bottom of the condensation chamber of this section are connected two pipes, one G, closed by a valve G², which as already described, leads back to the still, and another M, closed by a valve M¹ which leads to a 110

storage tank M^2 . On the pipe M below the valve M^1 is an automatic release valve M^2 set to release at such pressure as the operation of the system makes necessary. The 5 vapor pipe N from the top of the same condensation chamber, leads upwards to the top of a condensation section from the bottom of which a pipe O , closed by an automatic pressure release valve O^1 , leads to the 10 storage tank O^2 . The vapor pipe P leads upward from the top of the condensation chamber of this section to the uppermost condensation section, from the bottom of which the pipe Q , closed by a pressure release valve Q^1 , leads to the storage tank Q^2 . The vapor pipe R leads from the upper surface of the condensation chamber of the last section to the storage tank R^2 . Above R^2 is the gas storage tank X for uncondensed vapor. 15

If preferred, the storage tanks may be replaced by direct meter connections to a central system. The pipes M , O , Q and R leading from the condensation section to the storage tank, have jacketed about them a 20 cooler and condenser S , which may be brine coil, a water circuit, or the like. The automatic pressure release valves will be set normally to release at the same pressure. From the still A leads the pipe T , closed at either 25 end by the valves T^1 and T^2 . This pipe connects the still with the pipe R below a valve R^1 , and thus with the storage tank R^2 . This pipe is used to carry off the drippings or mixture of oil and water from the still, 30 which is discharged through the pipe R to the tank R^2 when it is carried off by pipes not shown before the oil itself begins to flow. A separate pipe, also not shown, will 35 of course be used to dispose of the oil which is later received by the tank R^2 . It will be understood that the number of condensation sections in the apparatus, which is here described as six, can be varied, and that the 40 number of sections connected directly to the storage tanks may be changed, without departing from the spirit of my invention, but 45 experience indicates that the arrangement here described and illustrated will be preferable. I desire that my drawings be taken 50 as in a sense diagrammatic, and it will be understood that many changes in number, shape, proportion, and disposition of parts can be made, all lying within the scope of 55 my invention.

The use and operation of my invention are as follows:—

The liquid to be refined is introduced into the still and vaporized in the usual way. When vaporization has sufficiently advanced, 60 the vapor rises to the pipe which leads from the top of the still, follows its curve, and enters the distribution pipe and radiator pipe of the first condensation section. There will be a considerable condensation in the 65 radiator pipe, but as the condensate and the vapor are both flowing downwardly, there is a minimum interference of the flow of the one with the other. The drip of condensates from the pipe gathers in the bottom of the condensation chamber, and, with the 70 condensate precipitated in the chamber, flows back to the still. It will be noted that the condensate is immediately removed from the chain or course of passage of the uncon- 75 densed vapor, and that the vapor is not im- peded in its passage by condensates, except in the condensation pipes; and in that short stretch the condensate and the vapor are flowing in the same direction. The size of the condensation chamber, which allows a 80 rapid expansion of the vapor, when the vapor is under pressure, promotes an immediate and complete separation of vapor and condensate. The vapor passes upwardly from the top of the condensation chamber, 85 and the condensate flows out at the bottom to find its level in the pipe below at the level of the oil in the still. Since the pipe dis- charges into the still below the oil level, there 90 is a constant circulation of oil, and no chance for the vapor under pressure to back up the oil in the run back pipe. This involves a great saving of fuel, since in the usual refin- 95 ing system the vapor has to be heated above the necessary point and kept under a higher pressure because it has to force itself through and against the course of the condensate. Of course no superfluous pressure is wasted in the actually harmful function of backing up the condensate in the run back pipe. An 100 important result of this complete separation of vapor and liquid is, that it is absolutely impossible for the vapor to carry with it in its upward course condensates of the heavier 105 grades, to mix with and reduce the value of the better grade of condensate of the upper radiation and condensation section. This is a difficulty met in the presently used sys- 110 tems where the vapor is filtered or forced through the condensate in a condensing tow- er, or through condensing sections. With my invention, no matter how great the pres- 115 sure of the gas, no low grade condensate can be carried upwards or kept standing in the condenser. It drains off by gravity, undis- turbed by any opposing flow of vapor, and an approximately complete separation of the varying grades of condensate is insured. The vapor passes successively through sev- 120 eral radiation sections, the condensate in each case draining back to the still. Fi- nally, in the fourth section as I have illus- trated it, though the number might be greater or less, I provide for drawing off the con- 125 densate either to the still, or to a storage tank. It will be understood that this condensate will be normally of relatively low grade. In some conditions it may be worth while draining it off directly to the storage tank rather than re-refining it. When the 130

valve to the pipe returning to the still is closed, and after the storage tank pipe is opened the condensate will gather above an automatic pressure release valve which is 5 provided below the gate valve, till its weight is enough to open the valve, and allow the liquid to drain off. I set the valve normally to open at a pressure as the operation of the system makes necessary, the pressure in the 10 system being usually at from 73 to 95 pounds, though other pressures might be used, in both cases. The essential point is that the valve is released at a pressure greater than that of the system, so that the mixed 15 vapor and condensate will not blow out through the pipe and into the storage tank instead of following the apparatus through to the end. For the same reason I provide the condensate discharge pipes of the upper 20 section of my apparatus which drain directly into the storage tanks with similar pressure and release valves. The vapor pipes from the last uppermost condensation section carries off the residue of the high 25 grade oil. This vapor is condensed by passage through the cooling and condensing section described earlier in the specification, which might be a system of brine coils, or cold water. In my apparatus fifty per cent 30 of the condensate will be discharged through this uppermost vapor pipe, and will normally reach a specific gravity of 65 or higher. A further feature of my invention is the fact that by the passage of gas or vapor 35 through the condenser box in which condensate backed up by the pressure valve is normally flowing, I add to the volume of this condensate through the absorption into the liquid of some of the vapor through which 40 it passes. The slower the oil passes through the coils of the condenser box the greater will be the increase in its volume by absorption since in my apparatus the condensate is always carried off by gravity, and since the 45 course of the vapor is unimpeded, I can operate my system at a pressure lower than that normally used. All I require is that the vapor rise and flow through the various condensation sections. This involves a saving 50 in fuel, and through the reduction of the heat, less danger of overheating the bottom of the still. This, of course, allows a longer continuous operation of the still. By the reduced pressure and the arrangement of 55 the condensation sections to separate the condensate from the vapor, all danger of carrying the lower grade distillate along with the vapor is obviated. Conversely, no excess pressure is required to force the vapor 60 through the condensate, and all these factors act together to reduce the heat and pressure needed, and at the same time to insure a higher grade of condensate from the upper condensation sections.

65 When the still is run at higher pressure,

that is to say at higher heat and with an exceedingly more rapid run of vapor and oil through the condensation sections the quality of the distillate from the top section will not be materially decreased in quality. There 70 will be a slight decrease in quality but a corresponding increase in volume from the two sections next the top section. There will, of course, be a far greater run back from the lower sections. Any dirt or foreign substance which is in the oil will gather in the lower condensation chambers with the heavy oils and cannot be carried upward through the various passages and upper condensation chambers. Such matter can 75 not be vaporized and the pressure of the vapor passing upward through the system is not sufficient to carry it far. This permits the delivery of oil to the storage tanks 80 free from settling.

I claim:—

1. In an apparatus for distilling hydro-carbons comprising a still and means for heating it, and a reservoir for receiving the distillate, a plurality of condensation sections arranged in series, a vapor pipe from the still to the first section, a vapor pipe from each section leading to the next section, condensate pipes leading from each section, those of the first sections leading back to 90 the still, and those of the later sections leading to the reservoir, a condenser, a vapor pipe on the last section leading therethrough to the liquid reservoir, automatic pressure relief valves in the condensate pipes leading 95 from the sections to the reservoir, said valves set at a pressure substantially above that of the condensation system.

2. The process of distilling hydro-carbons which consists in vaporizing the liquid and 105 passing it through a series of condensation zones, in returning for redistillation the condensate formed in some of the zones and in allowing the condensate from other zones to escape into a storage zone by gravity, 110 against pressure substantially higher than that of the condensation zones.

3. In an apparatus for distilling hydro-carbons comprising a still and means for heating it, and reservoirs for receiving the 115 distillate, a plurality of condensation sections arranged in series, a vapor pipe from the still to the first section, a vapor pipe from each section leading to the next section, condensate pipes leading from such 120 sections, automatic pressure relief valves in the condensate pipes, set at a pressure substantially above that of the condensation system.

4. In an apparatus for distilling hydro-carbons, a still and means for heating it, and a condensation section connected thereto, said section comprising a distribution member, a separation chamber beneath it, said chamber of far greater volume than said 130

distribution member, and a radiation member connecting the distribution member with the separation chamber, an oil run off pipe from the bottom of the chamber, an automatic relief valve in said pipe, set at a pressure substantially above that of the condensation system.

5. The process of distilling hydro-carbons which consists in vaporizing a liquid 10 and passing the vapor through a plurality of condensation zones, the vapor passing first through a restricted radiation zone and then directly into an enlarged separation zone, and then through a series of radiation and 15 separation zones similar to the first pair, and passing off the accumulated liquid

formed in the separation zones, against pressure higher than that of said zones.

6. The process of distilling hydro-carbons which consists in vaporizing a liquid and passing the vapor through a condensation zone, downwardly through a restricted radiation zone and then directly through an enlarged separation zone, and then upwardly from the top of said separation zone, and passing off the liquid accumulated in said separation zone against pressure higher than that of said zone. 20 25

ARTHUR C. ARMSTRONG.
